United States Patent Office

Des. 195,927
Patented Aug. 6, 1963

195,927

SPACE HEATER

John J. Fannon, Jr., Grosse Pointe Park, and Charles W. Sawyer, Ann Arbor, Mich., assignors to Hupp Corporation, Cleveland, Ohio, a corporation of Virginia

Filed Dec. 29, 1961, Ser. No. 68,118

Term of patent 7 years

(Cl. D81—10)

FIGURE 1 is a perspective view of the space heater of the present invention as viewed from beneath;

FIGURE 2 is a perspective view thereof as viewed from above; and

FIGURE 3 is a sectional view taken along line 3—3 of FIGURE 2.

The end not shown is substantially a mirror image of the end shown.

We claim:

The ornamental design for a space heater, substantially as shown and described.
